(57) **CLAIM**

The ornamental design for a palm frond antenna concealment insulated shaft as shown and described herein.

DESCRIPTION

FIG. 1 is a perspective view of a first embodiment of a palm frond antenna concealment insulated shaft showing the new design;

FIG. 2 is a top view of the first embodiment of the palm frond antenna concealment insulated shaft;

FIG. 3 is a side view of the first embodiment of the palm frond antenna concealment insulated shaft;

FIG. 4 is a perspective view of a second embodiment of the palm frond antenna concealment insulated shaft; and,

FIG. 5 is a perspective view of a third embodiment of the palm frond antenna concealment insulated shaft.

The broken line portion of the figure drawings is included to show portions of the article that form no part of the claimed design.

1 Claim, 4 Drawing Sheets
